GAME BOARD

Joseph B. King, Houston, Tex., assignor, by mesne assignments, of one-half to Fred H. Nichols, Houston, Tex.

Application March 31, 1939, Serial No. 265,212

2 Claims. (Cl. 273—131)

This invention relates to a game board.

An object of the invention is to provide a board for playing a game requiring skill and embodying a central playing field, approximately rectangular and two oppositely arranged fields, one for each player disposed on opposite sides of the central field and each formed with two sections disposed along side the corresponding margins of the central field, each of said fields containing series of holes to receive the playing pieces as the game is played.

More specifically, the invention comprises a game board having a central playing field, preferably rectangular, and having five series of holes, each series having five holes and the oppositely arranged player fields, hereinabove referred to, each composed of two sections and each section having two series of holes with five holes to the series thus making sixty-five holes in all, the holes of each series hereinabove referred to, preferably being in substantial alignment.

In a preferred form of the invention there is preferably delineated on the board a cross containing the central hole of the central section, and also the central hole of each series on each side of said central hole making five holes, in all, contained within said cross.

The invention also embodies a set of playing pieces, four less than the total number of holes and preferably in the forms of balls.

With the above and other objects in view the invention has particular relation to certain novel features of construction, arrangement of parts and use, an example of which is given in this specification and illustrated in the accompanying drawing, wherein—

Figure 1 shows a plan view of the board, and Figure 2 shows a cross-sectional view taken on the line 2—2 of Figure 1.

Referring now more particularly to the drawing wherein like numerals of reference designate the same parts in each of the figures, the numeral 1 designates the marginal frame for the board 2. There are the parallel cross-strips 3, 3 arranged on opposite sides of the board and spaced inwardly the required distance from the corresponding side members of the frame and forming the pockets 4, 4 for retaining the playing pieces 5 when they are not actively in the game being played. The numeral 6 designates the central field which is preferably rectangular and which is provided with five rows, or series, of holes as 7, each series containing five holes making twenty-five holes in all in the central field. The holes of each series are preferably, although not

necessarily, in alignment. The central hole 7a, of the field 6 and the central holes 7b of each series on each side of the central hole 7a are preferably located within a surrounding cross 8 delineated on the central field in any preferred manner. 5

There are the oppositely disposed player fields 9, 10. Each player field is composed of two sections 9a, 9a and 10a, 10a. The player fields are arranged diagonally opposite with respect to 10 the central field, as shown, and their sections lie adjacent the corresponding margins of said central field. The sections of the player fields are provided with two series of holes 11, each series containing five holes thus making ten holes in 15 each section. The series of holes of each section are preferably parallel and also parallel to the corresponding series of the central field.

The player fields, for convenience, are of different colors as indicated by Figure 1. 20

As hereinabove indicated the game is designed to be played by two players on opposite sides of the board. The sixty-one playing pieces are placed, one in the center hole 7a and the others in the holes outside of the cross 8, thus leaving 25 four vacant holes 7b. The object of the game is to clear the playing fields 9 and 10 of all playing pieces and the winner of the game is the one that first succeeds in clearing his field. It sometimes happens in the course of a game, that 30 neither player is able to completely clear his field and in that event the winner is the one having the smallest number of playing pieces in his field at the end of the game. If the game becomes blocked, that is if the playing pieces are so disposed that neither player can make another play and there are an equal number of playing pieces in the fields, 9 and 10, the game results in a tie. 35

It is to be observed that in playing the game, a player may originate a jump or play from his own 40 field or from the central field 6, but not from the field of the opposing player. A play may terminate, however, either in the center field 7 or in the player's field or in the opponent's field.

Upon beginning, the player having a designated section, as for example the red section 9, starts the game by jumping a playing piece over another into one of the vacant holes 7b the playing piece jumped is removed from the play. Thereupon the player having the blue field 10 50 executes a play in a similar manner and removes the jumped playing piece and the game is continued by the players alternately jumping a playing piece as above indicated, so long as it is possible to do so. A player may jump to block 55

an opponent's play, if possible, but the only play a player is permitted to make is to jump a playing piece and the movement of the played piece must be directly along a series of holes and not in a 5 diagonal direction. A player can make only one play at a time and must remove the playing piece jumped, the plays being made by the respective players alternately. There is this exception, however, that should a player be so maneuvered or so maneuver his pieces that when 10 his turn comes he can not make a jump, that player loses his turn and the opposing player, in that event, can make two or more successive plays until the other player is enabled to originate a 15 play, in keeping with the rules, and then that player can again play. A play is completed when the player removes his hand from the playing piece placed in a vacant hole and said play can not then be recalled. The player winning the 20 game is allowed to make the first play in the succeeding game.

The drawing and description are illustrative merely while the broad principle of the invention will be defined by the appended claims.

25 What I claim is:

1. A game apparatus comprising a game board having a rectangular central playing field, opposing player fields surrounding the central field and of colors distinguishable from each other and 30 from the central playing field, said opposite player field being each formed of two sections,

the two sections of one player field lying adjacent two sides of the central field and the two sections of the other player field lying adjacent the other two sides of the central playing field, the central field having five series of holes with five holes in each series and each section of a player field having five series of holes with two holes in each series, each series of holes in the central field aligning with a series of holes in each of said section on opposite sides of the central playing 1 field.

2. A game apparatus comprising a game board having a rectangular central playing field, opposing player fields surrounding the central field and of colors distinguishable from each other and 1 from the central playing field, said opposite player field being each formed of two sections, the two sections of one player field lying adjacent two sides of the central field and the two sections of the other player field lying adjacent 2 the other two sides of the central playing field, the central field having five series of player spaces with five player spaces in each series and each section of a player field having five series of player spaces with two player spaces in each 2 series, each series of player spaces in the central field aligning with a series of player spaces in each of said sections on opposite sides of the central playing field.
